US00D612127S

(12) **United States Design Patent**
Hall et al.

(10) **Patent No.:** US D612,127 S
(45) **Date of Patent:** ** Mar. 23, 2010

(54) **SURGICAL SCRUB PANTS WITH MESH**

(75) Inventors: **Carl Hall**, Chicago, IL (US); **Thea McSweeney**, Chicago, IL (US); **Paige Dellerman**, Neenah, WI (US); **Daniel Formosa**, Piermont, NY (US); **Matthew Grabowsky**, Warren, NJ (US); **Whitney Hopkins**, Vail, CO (US); **Michael Sarnowski**, Bristol, RI (US); **Jin Seo**, New York, NY (US)

(73) Assignee: **Allegiance Corporation**, McGaw Park, IL (US)

(**) Term: **14 Years**

(21) Appl. No.: **29/331,761**

(22) Filed: **Jan. 30, 2009**

(51) LOC (9) Cl. **02-02**

(52) U.S. Cl. **D2/742**; D2/739

(58) **Field of Classification Search** D2/742, D2/731, 738, 700, 739; 2/227, 228, 79, 80, 2/78.3, 236–238
